US00D618895S

(12) **United States Design Patent**
Wolff

(10) **Patent No.:** **US D618,895 S**
(45) **Date of Patent:** **** Jul. 6, 2010**

(54) **GOLF SHOE OUTSOLE**

D586,543 S * 2/2009 Wolff D2/954
D605,838 S * 12/2009 Foust D2/957

(75) Inventor: **Gary Wolff**, Fenton, MO (US)

* cited by examiner

(73) Assignee: **Wolff Shoe Company**, Fenton, MO (US)

Primary Examiner—Celia A Murphy

(**) Term: **14 Years**

(74) Attorney, Agent, or Firm—Paul M. Denk

(21) Appl. No.: **29/316,290**

(57) **CLAIM**

(22) Filed: **Sep. 10, 2009**

The ornamental design for the golf shoe outsole, as shown and described.

(51) **LOC (9) Cl.** **02-04**

DESCRIPTION

(52) **U.S. Cl.** **D2/955**; D2/954; D2/959

FIG. 1 is a perspective view of a golf shoe outsole showing my new design;

(58) **Field of Classification Search** D2/902,

FIG. 2 is a bottom plan view;

D2/947, 951, 954, 955, 959, 960; 36/3 B,

FIG. 3 is a top plan view;

36/25 R, 32 R, 34 R, 59 R, 67 A

FIG. 4 is a left side elevational view of the inverted sole;

See application file for complete search history.

FIG. 5 is a right side elevational view of said sole;

FIG. 6 is a rear view thereof; and,

FIG. 7 is a front view.

The broken lines immediately adjacent to the solid lines in FIGS. 3 and 7 represent an internal boundary of the design with the broken lines and the area within them forming no part of the claim.
